DESIGN FOR A BEAUTY HELMET

Rose Merkin, Newton, Mass.

Application November 10, 1937, Serial No. 72,762

Term of patent 14 years

To all whom it may concern:

Be it known that I, Rose Merkin, a citizen of the United States of America, residing at Newton, in the county of Middlesex, Commonwealth of Massachusetts, have invented a new, original, and ornamental Design for a Beauty Helmet, of which the following is a specification, reference being had to the accompanying drawing, forming part thereof, wherein

I claim:

The ornamental design for a beauty helmet, substantially as shown.

ROSE MERKIN.
